UNITED STATES PATENT OFFICE.

DAVID W. FERGUSON, OF HARROLD, SOUTH DAKOTA.

TRACE HOLDER.

Application filed May 10, 1922. Serial No. 559,941.

To all whom it may concern:

Be it known that I, DAVID W. FERGUSON, a citizen of the United States, residing at Harrold, in the county of Hughes, State of 5 South Dakota, have invented a new and useful Trace Holder; and I do hereby declare the following to be a full, clear, and exact description of the invention, such as will enable others skilled in the art to which it 10 appertains to make and use the same.

The invention relates to trace holders and has for its object to provide a trace holder which is attached to the girth and is provided with an outwardly extending lug on 15 which is pivotally connected arms terminating in hooks for the reception of adjacent trace loops, said arms having independent movement. The girth carried member is also provided with segmentally shaped guides 20 for guiding the loops in their movement in a vertical plane and a segmentally shaped member cooperates with the ends of the hooks for preventing displacement of the loops.

25 A further object is to provide means whereby when the hooked members are in a raised position the trace loops may be received thereby or unhooked.

With the above and other objects in view 30 the invention resides in the combination and arrangement of parts as hereinafter set forth, shown in the drawings, described and claimed, it being understood that changes in the precise embodiment of the invention 35 may be made within the scope of what is claimed without departing from the spirit of the invention.

In the drawing:

Figure 1 is a side elevation of the trace 40 holder.

Figure 2 is a top plan view of the trace holder, part being broken away to better show the structure.

Figure 3 is a vertical sectional view 45 through the trace holder taken on line 3—3 of Figure 1.

Referring to the drawing, the numeral 1 designates a conventional form of girth and 2 an annular member, the diametrically opposite sides of which are connected together 50 by the bar 3. The annular member 2 is secured to the girth 1 by means of the straps 4 and 5. The strap 4 arching the bar 3 and the strap 5 extending over the lower 55 side 6 of the annular member 2. Extending outwardly from the bar 3 is a headed lug

7 on which lug is pivotally connected by means of eyes 8 oppositely extending arms 9. The arms 9 at their outer ends are provided with hooks 10 which receive the trace loops 60 11, and are positioned where the trace loops during their movement upwardly and downwardly in a vertical plane will be held against rubbing engagement with the side of the animal 12. To additionally guide the 65 loops 11 the opposite sides of the annular members are provided with segmentally shaped guide rods 13 in the same plane as the annular member 2. The opposite extending arms 9 are additionally guided by 70 means of the guide bars 14, which extend across the annular member 2 and are off-set outwardly in a parallel plane in relation to the annular member 2. It will be seen that as the pivoted members 9 move upwardly 75 and downwardly during a draft operation that the pivoted members 9 will be positively guided in such a manner that rubbing of the sides of the animal is obviated. While the girth 1 has been described it is obvious that 80 any other kind of supporting means may be provided, for instance a back band.

The loops 11 are prevented from coming off the hooks 10 by means of offset segmentally shaped members 15 which members are 85 disposed adjacent the ends 16 of the hooks 10 and are concentric to the headed lug 7, therefore it will be seen that as the hooks 10 move upwardly and downwardly, the loop will be prevented from coming off of 90 the hooks 10. However to allow the loops 11 to be easily and quickly applied or removed from the hooks 10, the upper ends of the segmentally shaped members 15 extend 95 inwardly towards each other at 17, thence upwardly at 18, and thence inwardly and merge into the annular member 2, thereby forming open spaces 19, into which the hooks 10 are moved when it is desired to move or attach the loops 11.

From the above it will be seen that a trace holder is provided, which is simple in construction, positive in its operation and so constructed that trace loops may be easily and quickly attached or detached. Also that when the loops are attached that during a draft operation they will be positively held against unhooking.

The invention having been set forth what is claimed as new and useful is:—

1. A trace holder comprising an annular member, a bar carried by said annular mem-

ber and adapted to be attached to a support, an outwardly extending headed lug carried by said bar and disposed centrally in relation to the annular member, oppositely extending pivoted arms carried by said headed lug, the outer end of said pivoted arms terminating in hooks for the reception of trace loops, segmentally shaped guide members carried by the opposite sides of the annular member and disposed beneath the hooks, segmentally shaped outwardly offset hook engaging members carried by the opposite sides of the annular member and forming means for preventing displacement of loops on the hooks, the upper ends of said segmentally shaped outwardly offset hook engaging members terminating in inwardly extending portions thereby forming means for allowing easy removal of the loops from the hooks.

2. A trace holder comprising an annular member, means for attaching said annular member to a support, an outwardly extending headed member disposed centrally of the annular member, pivoted trace receiving hooks carried by the headed member and overlying the opposite sides of the annular member, concentrically disposed outwardly offset guide members carried by the annular member and cooperating with the hooks

for preventing displacement of trace loops, said concentrically disposed members at their upper ends terminating in inwardly extending portions thereby allowing the trace loops to be removed from the hooked members when moved in registration therewith. 35

3. A trace holder comprising an annular member, a centrally disposed headed lug, trace receiving hooks pivotally connected to the headed lug, segmentally shaped guide members at the opposite sides of the annular member, offset guide bars extending across the annular member and located outside of the pivoted hooked members, concentrically and oppositely disposed guide 40 members carried by the annular member and located adjacent the ends of the hooks, said concentrically disposed guide members having their upper ends extending inwardly and upwardly thereby forming means where- 45 by when the pivoted hooks members are moved upwardly the trace loops may be removed therefrom. 50

In testimony whereof I have signed my name to this specification in the presence of 55 two subscribing witnesses.

DAVID W. FERGUSON.
